BY, *Campbell & Co.* ATTYS.

UNITED STATES PATENT OFFICE.

FREDRICK MONIER, OF NEWARK, NEW JERSEY.

DESIGN FOR A BRIDLE-BIT.

SPECIFICATION forming part of Design No. 17,158, dated March 1, 1867.

Application filed October 8, 1886. Serial No. 915,736. Term of patent 7 years.

To all whom it may concern:

Be it known that I, FREDRICK MONIER, a citizen of the United States, residing at Newark, in the county of Essex and State of New Jersey, have invented and produced a new and original Design for Bridle-Bits, of which the following is a specification, reference being had to the accompanying drawings and to letters of reference marked thereon, which form a part of this specification.

In the said drawings, Figure 1 is a front elevation of my new and original design for a bridle-bit, illustrating more particularly the mouth-piece thereof; and Fig. 2 is a side elevation of said bit, showing more fully the cheek thereof.

The novel features of said design for a bit consist in the formation of the central port or link, *a*, and also, and more particularly, the configuration of the cheek pieces. In bits of this description as heretofore made the port has extended on but one side of the mouth-piece, the portion *a*, containing the roller *a'*, indicating said old feature, the main part of the mouth-piece *b* continuing from cheek to cheek in about a straight line.

In my new and original design the port extends oppositely on both sides of the mouth-piece, forming the portions *a* and *a'*. The said portions *a* *a'* may project at equal distances on opposite sides of the mouth-piece, or said portion *a'* may be shorter than the portion *a*, as shown.

An additional new feature in the design is the cheek-pieces *c*, which consist of a representation of a human leg which joins the mouth-piece at about the knee, said leg having a shoe, *e*, and stocking *d* thereon, as indicated. On the upper part of the leg is formed a strap-ring, *g*, and on the leg the end of the mouth-piece forms a cap or projection, *h*. These latter features, however, are not an essential part of the design of the cheek-pieces, which, as stated, consist of the outline of a human leg in a natural bent position, and, being attached to the mouth-piece at or near the knee, projects above and below the said mouth-piece, as shown.

I claim—

The design for a bridle-bit herein shown and described, consisting of a mouth-piece provided with oppositely-projecting portions *a* *a'*, and cheek-pieces presenting in side elevation the outline of a bent leg whose junction with the said mouth-piece is at or near the knee, substantially as set forth.

In testimony that I claim the design set forth above I have hereunto set my hand this 2d day of October, 1886.

FREDRICK MONIER.
